UNITED STATES PATENT OFFICE

170,061

HAT

Paul M. Maxwell, Milton, and Klari M. Wlach,
New York, N. Y., assignors to Hat Corporation of America, Norwalk, Conn., a corporation of Delaware

Application February 27, 1953, Serial No. 23,819

Term of patent 3½ years

(Cl. D3—13)

To all whom it may concern:

Be it known that we, Paul M. Maxwell and Klari M. Wlach, each a citizen of the United States, residing, respectively, at Milton, county of Ulster, and State of New York, and at New York, county of New York, and State of New York, have invented a new, original, and ornamental Design of a Hat, of which the following is a specification, reference being had to the accompanying drawing, forming part thereof.

Fig. 1 is a top view of a hat showing our new design.

Fig. 2 is a side view thereof.

We claim:

The ornamental design for a hat, as shown.

PAUL M. MAXWELL.
KLARI M. WLACH.
